UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

ELECTRIC LAMP.

1,283,731.

Specification of Letters Patent.

Patented Nov. 5, 1918.

Application filed September 11, 1916. Serial No. 118,355.

To all whom it may concern:

Be it known that I, CHARLES E. GODLEY, a citizen of the United States, and residing at Detroit, in the county of Wayne and State of Michigan, have invented a new and Improved Electric Lamp, of which the following is a specification.

This invention relates to electric lamps, to the bulb mountings therefor, to the couplings for the electric circuits, and particularly to the quick detachable coupling provided with a switch, and its object is to provide a lamp that can be easily adjusted, that will be simple in construction, and that will not get out of order with ordinary care. This construction is especially adapted for electric headlights and search lights for launches and automobiles, although the details thereof may be generally employed.

This invention consists, in combination with a novel coupling sleeve and means to hold it substantially rigidly in position; of a plug extending into one end of the sleeve and stationary relative thereto and having one or two contact posts, of a second plug extending into the other end of the sleeve and revoluble therein and having the same number of contacts as the first, the contact or contacts of one of the plugs being spring-pressed toward the other plug, and means to turn the revoluble plug within the sleeve so as to engage and disengage the contacts at will. It also consists in employing a collar on the outside of the coupling sleeve and a pin extending through a slot in said sleeve from the collar into the movable plug to turn it. It further consists in so forming the slot in the coupling sleeve that the movable plug and collar will be held in either of two predetermined positions. It further consists in a novel focusing device for the lamp bulb, and in the details of construction illustrated in the accompanying drawings and particularly pointed out in the claims.

In the accompanying drawings. Figure 1 is a central section of this improved search light. Fig. 2 is a longitudinal section of a connector. Fig. 3 is an elevation of the coupling sleeve and of the end of a plug of this connector. Fig. 4 is an end elevation of the connector. Fig. 5 is a section on the line 5—5 of Fig. 3.

Similar reference characters refer to like parts throughout the several views.

In Fig. 1, the casing 1 of the lamp is

shown to receive the lens ring 2 which presses the lens 3 against the packing ring 4 carried in a groove in the outer flange 5 of the reflector 6. A handle 7 is formed on the casing and within it is revolvably mounted a screw 8 having a knob 9 at its outer end. A coupling sleeve 10 is slidable in a cylindrical flange 12 at the rear end of the reflector, which flange has a horizontal slot 13 to receive the bar 14 secured to the sleeve 10, whereby the sleeve is prevented from turning. A lamp bulb 15 of any desired type is mounted in the front end of the sleeve, while the well known insulating plug 16 is provided with contacts to which the wires 17 and 18 are joined by means of the screws 19. The rear end 20 of the bar 14 is turned in and threaded to receive the screw 8. A pin 22 may be used to prevent the screw being turned entirely out of the hole in the end 20. A spring 23 around the screw 8 acts as a brake to restrain the screw from turning. It will be seen that this simple mechanism permits the lamp bulb to be perfectly focused.

The casing is shown formed with a cylindrical flange 25 within which the coupling sleeve 26 is securely held by means of a circumferential spring 27, one end of which lies in a notch in the flange 25 and has an inwardly turned lip 28 that extends into a notch in the coupling sleeve. This spring can easily be removed to release the coupling sleeve.

The well known plug 29 of insulating material is provided with three pins 30 that are adapted to engage in the bayonet slots 31—32 in the sleeve 26 in the usual manner. This plug has metal conductor cores 33 in which the conductor posts 34 are slidable, being normally held out by the springs 35. A second plug 36 of insulating material is provided with stationary conductor posts 37 and is revoluble and slidable in the sleeve 26, being held therein against the pressure of the posts 34 and springs 35 by means of a pin 38 that passes through the curved slot 39 in the sleeve and is firmly secured in the collar 40 that is revolvably mounted on the sleeve. The ends of the slot 39 are preferably formed with sockets or notches for the pin 38 which will be held in either one or the other by the pressure of the springs 35. The wires 17 and 18 connect to the posts 37 by means of the screws 42.

When the parts are in the positions shown in Fig. 2, the springs 35 and post 34 will tend to press the plug 36 out of the sleeve 26, which movement will be regulated by the 5 pin 38 in the slot 39. Because of the curvature of this slot and the seats at its ends, movement of the pin 38 out of either of these seats is only possible upon application of considerable turning force to the collar 40. When the pin 38 is in the seat at one end of the slot, the posts 34 and 37 will engage, but when the pin is at the other end of the slot, the pins of the two sets will be separated ninety degrees and the electric 10 circuits will be broken. The construction is very simple and effective and the switch easily operated.

In case the casing 1 of the lamp is grounded, only one wire 17—18 is necessary, 15 and therefore one of each of the parts 33, 34, 35, 37 and 42 may be omitted.

A boss 50 of sheet metal may be secured to or formed on the casing 1 and have a flat circular end or top 51. A bolt 52 having a nut 53 extends through a hole in the part 51 and through a spring washer 54, a flange 55 on the bracket 56 and a second washer 57. This construction permits the lamp to be turned on the bolt 52 as a pivot. 20 The bracket 56 has a second flange 58 at right angles to the first and through this and through the flange 59 on the support 60 extends a bolt 61 having a nut 62. A spring washer may also be placed under the head 25 of this bolt. A jaw 63 on this support may engage the bar 64, a second jaw 65 and bolt 66 completing the engagement. It will therefore be seen that the lamp may be 30 swung in a circle about the bolt 61 and in a circle at right angles to the first about the bolt 52, the combination of the two movements permitting the beam of light from the bulb 15 to be thrown in substantially every 35 direction.

40 Many changes in the details of construction may be made by lamp makers without departing from the spirit of my invention as expressed in the claims.

I claim:

45 1. The combination of a cylindrical coupling sleeve, a lamp bulb mounted in one end thereof, a bar secured to the sleeve and

having an inwardly turned free end provided with a threaded hole, a casing surrounding the lamp bulb and having a hollow extension, a screw mounted in said extension and in said hole in the bar, and a compression spring on the screw engaging the end of the bar and the end of the extension. 55

60 2. The combination of a lamp casing having a hollow rearwardly projecting central extension, a reflector mounted in the casing and having a cylindrical flange provided with a slot, a connector sleeve slidable within the flange, a bar connected to the connector sleeve and slidable in the notch in the flange on the reflector which thereby prevents the sleeve from turning, said bar being formed with a threaded hole, a screw 70 mounted in said hollow extension on the casing and screwed into the threaded hole in the bar, a knob on the outer end of the screw whereby it may be turned to slide the sleeve, and means to restrain the movement of the 75 screw.

3. In a lamp, the combination of a lamp casing having a hollow central extension, a reflector mounted in the casing and having a central opening, a lamp socket slidable in 80 said opening, a rearwardly extending bar secured to the socket and having an inwardly turned rear end provided with a threaded hole, a screw centrally and revolvably mounted in the extension of the casing and engaging in the threaded hole in the bar, and a compression spring mounted on the screw. 85

4. In an electric lamp, the combination 90 of a casing and a universal mounting therefor, a hollow central extension on the casing adapted to serve as a handle to swing the casing, a reflector in said casing and a rearwardly extending sleeve centrally mounted thereon, a focusing screw revolvably mounted in said handle, a spring on said screw within the handle to restrain the screw from turning, a lamp socket slidable in the sleeve on the reflector, and a threaded bar connecting to the socket and to said screw whereby 100 the turning of the screw may move the socket. 95

CHARLES E. GODLEY.
